CLUETT, PEABODY & CO., INC., OF TROY, NEW YORK, A CORPORATION OF NEW
YORK.

SOFT FOLD-COLLAR.

1,112,033.

Specification of Letters Patent.

Patented Sept. 29, 1914.

Application filed November 13, 1912. Serial No. 731,084.

To all whom it may concern:

Be it known that I, JULIA ROBINSON, a citizen of the United States, residing at Troy, county of Rensselaer, and State of New York, have invented certain new and useful Improvements in Soft Fold-Collars, of which the following is a specification.

The invention relates to such improvements, and consists of the novel construction hereinafter described and subsequently claimed.

Reference may be had to the accompanying drawings, and the reference characters marked thereon which form a part of this specification. Similar characters refer to similar parts in the several figures therein.

Figure 1 of the drawings is a view in perspective of a soft fold-collar embodying my invention. Fig. 2 is a plan view of one corner of the top-plies of the collar with my improved stiffening strip and said plies secured together by a run seam. Fig. 3 is a cross-section of the same taken on the broken line 3-3 in Fig. 2. Fig. 4 is a cross-section of the top of the fold-collar taken on the broken line 4-4 in Fig. 1. Fig. 5 is a front view of the front-portion of a fold-collar partly broken away, showing my invention used in connection with a link tying together the neighboring ends of a collar-top. In Figs. 3 and 4 the dimensions are exaggerated for convenience of illustration.

The soft fold-collar which has come into quite extensive use has some objectionable features, one of the most important of which is the untidy and disordered appearance which the front ends of the collar-top present when disarranged by the knot of the necktie and the movements of the wearer. This is due largely to the fact that such collars are made of soft flexible fabrics which lack the strength and stiffness which is necessary to retain said ends symmetrically disposed. In the endeavor to hold the ends of the top of such a collar symmetrically and smoothly disposed, various expedients have been adopted for the purpose of tying together the ends of the top or fastening the ends of the top to the neckband as by means of buttons and buttonholes, but it is impossible by the use of such devices to hold the neighboring ends of the top in even approximate symmetry.

The principal object of the present invention

is to impart to the neighboring end-edges of the top of a soft fold-collar such stiffness as will enable them to maintain in use substantially the desired symmetrical relationship. To this end, I incorporate in the folded end-edges of the top, folded reinforce strips inclosed and stitched between the plies of the top in such a manner as to form along each end-edge of the top a zone of much greater thickness than at other points in the top.

Referring to the drawings wherein the invention is shown in preferred form, 1 represents the band and 2 the folded-over top of a soft fold-collar. The neighboring ends of the top are reinforced and stiffened by zones of increased thickness between the dotted lines 3-3 and the respective end-edges of the top. The top is shown formed of three plies, 4, 5, and 6, which in making the collar are stitched together wrong side out by a run seam, 7. A longitudinally folded reinforce or stiffening strip, 8, is superimposed upon the plies along their end-edge and secured to the plies by said run seam, 7, the relative positions being shown in Figs. 2 and 3. After the running operation, the top is turned right side out by hand, thus locating the reinforce strip, 8, between the plies as shown in Fig. 4, increasing by four thicknesses of the strip, 8, the thickness of the extreme edge-portions of the ends of the top, and increasing by two thicknesses of the reinforce strip the thickness of the top inwardly to the point, 3. The plies of the top and the reinforce strip, 8, after being turned right side out are stitched together along the lines, 9. The increased zones of thickness thus formed along the end-edges of the top render said edges to a large extent self-supporting to maintain a symmetrical disposition in use, and this without detracting from the soft effect of the collar upon the neck.

The collar may be worn without the use of devices for tying together the ends of the top or devices for securing the ends of the top to the band, or it may be used with any of such devices for securing together either directly or indirectly the ends of the top, rendering such devices more effective for the intended purpose.

In Fig. 5 I have shown my improved collar with the ends of its top tied together by

a link, 10, having buttons, 11, inserted through the respective buttonholes, 12, in the ends of the collar-top.

The reinforce strip may be made of any suitable fabric which will impart to the ends of the collar the necessary stiffness, heavy muslin or duck being suitable for the purpose.

What I claim as new and desire to secure 10 by Letters Patent is—

1. A soft-fold-collar having a folded-over top formed of a plurality of plies inturned and secured together along their edges, and a reinforcing strip having an edge portion 15 stitched to, and inturned between, the respective edge portions of the top along its ends and extending to a greater distance from the end of the top than do the inturned edges of the top plies.

2. A soft fold-collar having a folded-over top formed of a plurality of plies inturned and secured together along their edges, and a reinforcing strip folded along its longitudinal middle and having its edge portions

stitched to, and inturned between, the respective edge portions of the top along its ends, said strip having its folded edge portion extending further inward from the end of the top than do the inturned edges of the top plies, said folded edge and top plies being connected together by a line of stitching extending along the inner side of said inturned top ply edges.

3. A soft fold-collar having a folded-over top formed of a plurality of plies inturned and secured together along their edges, and having a reinforcing strip stitched to, and inturned between, the respective edge-portions of the top along its ends, said top having means whereby its ends are adapted to be secured together.

In testimony whereof, I have hereunto set my hand this 31st day of October, 1912.

JULIA ROBINSON.
